[57] CLAIM

The ornamental design for a doll, substantially as shown and described.

DESCRIPTION

FIG. 1 is a front elevational view of a doll showing our new design;

FIG. 2 is a right side elevational view thereof;

FIG. 3 is a rear elevational view thereof;

FIG. 4 is a top plan view thereof; and

FIG. 5 is a bottom plan view thereof.

The left side elevation is the mirror image of FIG. 2.

The entire body is covered with long hair except for certain panels which are covered with short pile fur as indicated in the drawing.

FIG. 1.

FIG. 2.

FIG. 3.

FIG. 4.

FIG. 5.
